UNITED STATES PATENT OFFICE

158,507

ARMCHAIR OR THE LIKE

Herbert Ritts, Los Angeles, Calif.

Application February 26, 1949, Serial No. 1,114

Term of patent 14 years

(Cl. D15—1)

To all whom it may concern:

Be it known that I, Herbert Ritts, a citizen of the United States of America, residing at Los Angeles, in the county of Los Angeles, State of California, have invented a new, original, and ornamental Design for an Arm Chair or the like, of which the following is a specification, reference being had to the accompanying drawing, forming a part thereof.

I claim:

The ornamental design for an armchair or the like, substantially as shown.

HERBERT RITTS.
